UNITED STATES PATENT OFFICE.

JEAN B. DAUDELIN, OF FALL RIVER, MASSACHUSETTS.

HAND-THREADING LOOM SHUTTLE.

1,413,102.

Specification of Letters Patent. Patented Apr. 18, 1922.

Application filed January 4, 1921. Serial No. 434,883.

To all whom it may concern:

Be it known that I, JEAN B. DAUDELIN, a citizen of the United States, residing at Fall River, county of Bristol, Commonwealth of Massachusetts, have invented certain new and useful Improvements in Hand-Threading Loom Shuttles, of which the following is a specification.

This invention relates to hand threading 10 loom shuttles and particularly to the eye piece for the threading eye. My invention involves certain improvements over the eye piece shown in my prior Patent No. 1,248, 627, December 4, 1917, to which reference 15 is made as illustrating the particular type involved herein. The present invention contemplates certain improvements whereby the eye piece is more securely fixed in the threading eye and also involves certain refinements in the construction of the eye piece itself, all as will appear more fully 20 hereinafter.

The construction and operation of my device, together with a selected embodiment 25 which well illustrates the principles of my invention, is described in the following specification and particularly shown in the drawings forming a part thereof. Throughout the specification and drawings like reference characters are employed to indicate corresponding parts, and in the drawings:—

Fig. I is a partial plan view of the threading end of a shuttle equipped with my invention.

Fig. II is a side elevation thereof as viewed from the right in Fig. I.

Fig. III is a similar elevation as viewed from the left in Fig. I.

Fig. IV is a transverse section on the 40 line IV—IV, Fig. I.

Figs. V and VI are perspective views of the eye piece removed and viewed from opposite sides, and

Fig. VII is a detail view of the guard 45 at the shuttle throat, removed.

I have indicated at 1 the body of a hand threading shuttle of standard type having a bobbin chamber 2 within which is mounted a bobbin 3 carrying the filling F. The 50 throat of the shuttle opens into an eye 4 which extends across the shuttle as a transverse bore of substantially cylindrical form, and is counterbored as clearly shown in Fig. III. Leading from the shuttle throat is 55 the usual threading slot 12 which extends

forwardly along the upper face of the shuttle, as appears in Fig. I, to the side wall thereof and thence downwardly and backwardly along said side wall to connect with the outer end of the threading eye, as appears in Fig. III.

As here shown, the eye piece 6 is a solid member preferably of porcelain, constructed and arranged to permit the shuttle to be rapidly and easily threaded and when threaded to effectively guide the filling directly from the bobbin through the shuttle eye.

In order to securely fix the eye piece within the eye, it has been the usual practice heretofore to conform the eye piece accurately to the shape of the eye so as to fit snugly therein. This has been difficult and unsatisfactory and accordingly one feature of my invention consists in an eye piece which while relatively loosely fitting the eye, is nonetheless securely fixed therein.

According to my invention the eye piece need not be shaped to snugly fit the eye but instead may loosely fit therein, mechanical means being provided to positively fit the eye piece within the eye. Such eye piece as here shown is formed as a substantially cylindrical lower section 7 and a rounded upper section 8, conforming roughly to the shape of the eye itself. The section 7 at the far side of the shuttle (see Fig. III) is longitudinally grooved as indicated at 9, Fig. V, to receive a horizontally disposed securing pin 99 and on its 80 opposite side is vertically grooved as indicated at 10, Fig. VI, to receive a vertical securing pin 100. The pins 99 and 100 thus fix the eye piece against both longitudinal 85 and lateral movement in the eye.

Between its ends and substantially in line with the axis of the bobbin the eye piece is vertically slotted as indicated at 11 providing a port through which the filling from the bobbin runs. In threading, the filling runs from the bobbin under a curved guard pin 17 to the port 11 and thence into the threading slot 12 of the shuttle which lays it into the eye piece from above the outer or delivery end thereof. The eye piece at its delivery end is cleared away at one side of its longitudinal axis, as indicated at 18, Fig. VI, and opposite said cleared portion 18 has an upwardly curved lip portion 13 which extends above the plane of entry of 110

the slot 12 into the eye and directs the filling into the eye piece. From said portion the filling descends into a port 14 communicating with the port 11 and spaced therefrom by a guide and snubbing post 15. The shuttle is now threaded. After threading, the filling runs directly from the bobbin through the port 11 around the base of the snubbing post 15 and out through the port 14 under the overhanging deflecting portion 13 of the eye piece, which portion 13 thus acts as a guard to prevent dethreading of the shuttle by an upward escaping movement of the filling. At the delivery end of the eye is set a guide post 16 which with the opposed face of the eye piece at its delivery end defines the path of travel of the filling.

The guard 17 is set across the shuttle throat in advance of the inlet port 11, and may be a simple pin having a pointed entering end and a bent guarding end which may be carried down into the wood of the shuttle so as to form an overlying curved bar under which the filling runs from the bobbin.

Various modifications in the form and construction of my device may obviously be resorted to all without departing from the spirit of the invention if within the limits of the appended claims.

What I therefore claim and desire to secure by Letters Patent is:—

1. An eye piece for a shuttle eye, consisting of a member having a thread passage terminating in spaced ports and having a guiding portion between said ports and overhanging the passage connecting said ports, said eye piece beyond said guiding portion cleared away at one side of its longitudinal axis, and a lip on said eye piece at the opposite side of its longitudinal axis and overhanging said cleared away portion and effective to lay the filling into the eye piece from above in threading and to prevent escape of the filling by a direct upward movement after threading.

2. In a shuttle having a threading eye, an eye piece loosely fitting said eye and having angularly disposed grooves, securing pins disposed in said grooves and fixing the eye piece against longitudinal and lateral movement in said eye, said eye piece having its delivery end cleared away at one side of its longitudinal axis and opposite said cleared portion having an upwardly disposed lip effective to lay the filling into the eye piece from above in threading and to prevent escape of the filling by a direct upward movement after threading.

3. In a shuttle having a threading eye, an eye piece loosely fitting said eye and having vertically and horizontally disposed grooves on opposite faces thereof, and securing pins disposed in said grooves and fixing the eye piece against longitudinal lat-

eral movement in said eye, said eye piece having its delivery end cleared away at one side of its longitudinal axis and opposite said cleared portion having an upwardly bent lip overhanging said cleared portion and effective to lay the filling into the eye piece from above in threading and to prevent escape of the filling by a direct upward movement after threading.

4. An eye piece for a shuttle eye, consisting of a solid member having a substantially cylindrical lower portion and a reduced rounded upper portion, there being a longitudinally extending groove between said upper and lower portions, and a securing element disposed in said groove to fix the eye piece in the shuttle eye.

5. An eye piece for a shuttle eye, consisting of a solid member having a substantially cylindrical lower portion and a reduced rounded upper portion, there being a longitudinally extending groove between said upper and lower portions, and a securing element disposed in said groove to fix the eye piece in the shuttle eye, said groove for a portion of its extent constituting a thread passage.

6. An eye piece for a shuttle eye, consisting of a solid member having a lower portion and an upper portion, there being a longitudinally extending groove between said upper and lower portions, and a securing element disposed in said groove to fix the eye piece in the shuttle eye, said groove for a portion of its extent constituting a thread passage.

7. An eye piece for a shuttle eye, consisting of a solid member having a substantially cylindrical lower portion and a reduced rounded upper portion, there being a longitudinally extending groove between said upper and lower portions, said upper portion of the eye piece having a slot between its ends providing a threading port and beyond said slot providing a guiding element, and said groove connecting the threading port with the delivery end of the eye piece.

8. An eye piece for a shuttle eye, consisting of a solid member having a substantially cylindrical lower portion and a reduced rounded upper portion, there being a longitudinally extending groove between said upper and lower portions, said upper portion of the eye piece having a slot between its ends providing a threading port and beyond said slot providing a guiding element, and said groove connecting the threading port with the delivery end of the eye piece and said lower portion of the eye piece beyond said guiding element disposed as a guard lip.

9. An eye piece for a shuttle eye, consisting of a solid member having a substantially cylindrical lower portion and a reduced rounded upper portion, there being a longi-

tudinally extending groove between said upper and lower portions, and a securing element disposed in said groove to fix the eye piece in the shuttle eye, said upper portion of the eye piece having a slot between its ends providing a threading port and beyond said slot providing a guiding element, and said groove extending past the base of said guiding element, and connecting the 10 threading port with the delivery end of the eye piece.

10. An eye piece for a shuttle eye, consisting of a solid member having a substantially cylindrical lower portion and a reduced 15 rounded upper portion, there being a longitudinally extending groove between said upper and lower portions, and a securing element disposed in said groove to fix the eye piece in the shuttle eye, said upper portion of the eye piece having a slot between its ends providing a threading port and beyond said slot providing a guiding element, and said groove extending past the base of 20 said guiding element, and connecting the 25 threading port with the delivery end of the eye piece, and said lower portion of the eye

piece beyond said guiding element disposed as a guard lip.

11. An eye piece for a shuttle eye, consisting of a solid member having a lower portion and an upper portion, there being a longitudinally extending groove between said upper and lower portions, and a securing element disposed in said groove to fix the eye piece in the shuttle eye, said upper portion of the eye piece having a slot between its ends providing a threading port and beyond said slot providing a guiding element, and said groove extending past the base of 30 said guiding element, and connecting the 35 threading port with the delivery end of the eye piece, and said lower portion of the eye being cleared away, and a guard lip on said lower portion of the eye piece overhanging 40 said cleared away portion.

In testimony whereof I affix my signature in presence of two witnesses.

JEAN B. DAUDELIN.
